CLAIM

The ornamental design for a coordinate acquisition member of a portable coordinate measurement machine, as shown and described.

DESCRIPTION

FIG. 1 is a perspective view of a coordinate acquisition member of a portable coordinate measurement machine showing our new design in accordance with a first embodiment of the invention;

FIG. 2 is a front view of the coordinate acquisition member of a portable coordinate measurement machine as shown in FIG. 1;

FIG. 3 is a rear view of the coordinate acquisition member of a portable coordinate measurement machine as shown in FIG. 1;

FIG. 4 is a left side view of the coordinate acquisition member of a portable coordinate measurement machine as shown in FIG. 1;

FIG. 5 is a right side view of the coordinate acquisition member of a portable coordinate measurement machine as shown in FIG. 1;

FIG. 6 is a top view of the coordinate acquisition member of a portable coordinate measurement machine as shown in FIG. 1; and,

FIG. 7 is a bottom view of the coordinate acquisition member of a portable coordinate measurement machine as shown in FIG. 1.
